GAS COMPRESSOR

Joseph F. Winkler, Philadelphia, Pa.; Alma Stamborger Winkler, executrix of said Joseph F. Winkler, deceased, assignor to Winkler, Margenthaler, Inc., Philadelphia, Pa., a corporation of Pennsylvania

Application September 24, 1946, Serial No. 699,054

1 Claim. (Cl. 230—58)

1

My invention relates to a radial gas compressor especially designed for compressing refrigerant gases, but which can also be used for compressing air and other gases.

One object of the invention is to produce an improved compressor of the type set forth.

A further object is to produce an electric motor-driven radial compressor which can be built and installed at less cost than comparable apparatus; which can be built in any capacity; which will be light and compact; which will operate relatively quietly and with no objectionable vibration, and which is completely explosion-proof, self-contained and hermetically sealed, and which may be operated completely submerged in water if necessary.

A still further object is to produce a compressor in which the motor and the lubricant are effectively cooled and in which all moving parts are flooded with lubricant as long as the compressor is in operation.

A still further object is to produce a compressor which is direct-driven so that no pulleys, belts, idlers, gears, flexible couplings or other extraneous connecting or driving devices are needed; which has no packing glands or shaft seals; which requires no special foundation or supporting base, and which has no water jacket which may freeze and burst or which may leak.

A still further object is to produce a compressor which may have its volumetric capacity modulated from almost zero to substantially one hundred per cent of capacity, and one which operates at about ninety per cent volumetric efficiency at one hundred pounds per square inch gauge pressure, and at about seventy-five per cent volumetric efficiency at three hundred pounds per square inch gauge pressure.

A still further object is to produce a radial, multiple cylinder compressor in which the cylinders are provided with resiliently mounted false heads; in which no bolts and nuts or other fastening devices are used on any moving parts; in which all parts are easily and readily dismantled or assembled, and in which all moving parts are symmetrical and interchangeable, whereby the cost of initial manufacture and the cost of servicing in the field are greatly reduced, and whereby the skill required in servicing the compressors is minimized.

A still further object is to produce a compressor in which the number of moving parts and the friction factor are both minimized, thus effecting considerable saving in wear and in motive power.

These and other objects are attained by my

invention as set forth in the following specification and as illustrated in the accompanying drawings, in which:

Fig. 1 is a vertical section of a radial compressor embodying my invention, looking in the direction of line 1—1 on Fig. 2.

Fig. 2 is a top plan view of the compressor shown on Fig. 1, certain parts being broken away to show details of construction.

Fig. 3 is a fragmentary top plan view showing the parts as they appear after the shaft has turned through an angle of ninety degrees from the position shown in Fig. 2.

Fig. 4 is an enlarged vertical sectional view of the inner portion of one of the cylinders.

In Fig. 1, there is shown a vertically-disposed radial compressor with the base 10 thereof resting on a floor, platform or any other available support 12, the base being preferably firmly secured to the support by means of bolts passing through holes 14 and engaging the support 12. Note that the compressor must be in a vertical position for it to operate satisfactorily. The compressor is housed in a casing 16, the bottom end of which is provided with a centering and sealing rim which rests upon a gasket placed in an annular recess formed in the top of the base 10, as at 18, and the casing is secured to the base by bolts 19.

The casing 16 is provided with external ribs for reinforcing the structure and for dissipating heat, and with spaced internal ribs or pads 22 to which the stator 24 of a polyphase electric motor is secured by bolts 25. Within the stator is the rotor 26 which is keyed to a shaft 28 extending vertically through the casing. The shaft 28 is provided with a through bore 29, the upper end of which discharges into a crankcase 30 and the lower end of which communicates with a chamber 32. A nut 33 helps support the rotor on the shaft.

On the lower portion of the shaft is mounted a rotary pump 34, which is keyed to the shaft at 35 and which draws and discharges through vertical ducts 36 and 37 which communicate, at their lower ends, with horizontal ducts 38 and 39, respectively. The inner ends of the ducts 38 and 39 lead to the chamber 32 and are closed by pivoted check valves 40 and 41. The outer ends of the ducts 38 and 39 lead into housings 42 and 43 disposed in a lubricant sump 44 formed in the lower portion of the base 10. The housings 42 and 43 are provided with bottom inlet openings 45 which are closed by gravity-operated plate valves 46. When the pump is rotated in one direction, pressure develops in one of the ducts 36 or 37. This pressure forces one of the valves 40 or 41 to open

and the lubricant moved by the pump is forced up through the bore 29 of the shaft 28 into the crankcase 30. This action of the pump results in reduced pressure above the plate valve 46 in one of the housings 42 or 43 and causes such valve to lift off its seat, thus allowing lubricant from the sump 44 to be drawn in through the inlet opening 45 of the particular housing 42 or 43.

When the direction of the rotation is reversed, pressure will develop in the other of the ducts 36 or 37 and the other of the valves 40 and 41, and the valve 46 closing the inlet opening 45 in the other of the housings 42 or 43 is opened. It will be understood that when one of the valves 40 or 41 and its associated inlet valve 46 are open, the other of the valves 40 or 41 and its associated inlet valve 46 will be closed. By this arrangement, the direction of rotation of the motor may, deliberately or accidentally, be reversed and the apparatus will continue to be lubricated. Where a single directional lubricating pump is used, incorrectly wiring the motor will cause the compressor to operate without lubricant, and this condition may not be detected until the apparatus has been seriously damaged or altogether destroyed. Test cocks (not shown) may be used for indicating the lubricant level in the sump 44.

The casing 16 is provided with an inlet 47 through which the gas to be compressed is admitted. The gas admitted through the inlet 47 flows upwardly, through the spaces 49, provided between the ribs 22, to the suction ports of the cylinders, which will be described later. The gas, especially when it is a low pressure refrigerant gas withdrawn from the evaporator of a refrigerating apparatus, flows around, and effectively cools the motor, and because it also flows past or through the return lubricant which overflows from the crankcase 30 through one or more pipes 58, it also cools the lubricant. In this connection it is also pointed out that the contact of the low pressure refrigerant with the motor and the lubricant will, under most normal circumstances, insure complete evaporation of any liquid refrigerant which may have entered the casing through the inlet 47. This guards against large amounts of liquid entering the compression cylinders.

The crankcase 30 is formed integral with a cylinder casting 51 secured to the upper end of the casing 16 by bolts 52, and a tight joint is produced by the means of a centering rim and a gasketed recess as shown at 12a. The casting 51 also carries a radial and thrust ball bearing 53 and a lubricant seal 53A which prevents lubricant from flowing onto the rotor 26. The only pressure against this lubricant seal is that caused by the height of the lubricant in the crankcase 30 as the gas pressure in the crankcase 30 and the gas pressure in the motor casing 16 are the same.

The cylinder casting 51 is cored to provide an inner, low pressure chamber 54 which houses the crankcase and communicates with the interior of the casing 16 and with the gas inlet 47 through the passages 49. Also cored into the cylinder casting 51 is a high pressure chamber 56, from which the compressed gas is discharged through an outlet 57.

The cylinder casting 51 is also provided with a plurality of chambers 58 for accommodating the compression cylinders. In the present instance, there are six such chambers, only one of which is shown in detail in Fig. 2. Each chamber 58 is provided with an annular seat 59 for engaging the inner end of a separable sleeve or cylinder

liner 60, and with an annular shoulder 62 for engaging a correspondingly shouldered annular portion 63 near the outer end of the cylinder liner. The outer end 64 of the chamber 58 is closed by a head plate 65 which is secured in position by bolts 66.

The outer portion of each cylinder liner is provided with a suction port 68 which is controlled by a ring type suction valve 70, and which communicates with the low pressure chamber 54, and with the interior of the casing 16, through the passages 49. The suction valve 70 is seated in a recess formed in an annular member 72, the inner face of which forms a continuation of the outer end of the cylinder liner 60. If desired, each cylinder may have a plurality of suction parts all of which will be controlled by the suction valve 70. Each of the cylinders is also provided with one or more discharge outlets which are controlled by a ring type valve 69 seated in a recess formed in a valve plate 74 which abuts the annular member 72.

The ring-type discharge valve shown requires a seat to limit its movement in the direction of the piston. If a seat is provided in the usual manner, there will be a clearance between the outer face of the piston and the inner face of the valve, which clearance results in reduced volumetric efficiency. To overcome this difficulty, I secure to the inner side of the plate 74 a rounded member 76. Conveniently, a bolt having a relatively large round head is used and is so disposed that the outer flat periphery 77 of the bolt head 76 serves as seat for the inner periphery of the valve 69, the outer periphery of the discharge valve 69 being adapted to seat against the adjacent outer face 79 of the annulus 72. When the piston is at the end of its compression stroke, the round head 76 of the bolt fits snugly in a recess formed in the outer end of the piston. By this construction the space or clearance left between the outer face of the piston and the inner face of the plate 74 is so small that, when the compressor is operating at one hundred pounds gauge pressure, its volumetric efficiency will be about ninety per cent, and when the compressor operates at three hundred pounds gauge pressure, the volumetric efficiency will be about seventy-five per cent.

The discharge valve plate 74 also serves as a false head for the cylinder and is backed by a spring 80 confined between this valve plate and the outer head 65. The spring 80 is strong enough to seat the valve plate 74 firmly against the annulus 72, and is weak enough to yield under impact so as to avoid injury to the parts. For example, if one of the valve reeds should break, or if some other solid matter or a slug of liquid refrigerant should lodge between the piston 78 and the discharge valve 69, or between the piston 60 and the round surface of the bolt head 76, the spring 80 will yield and will thus prevent serious injury. The round head of the bolt 76 also facilitates ejection of solid or liquid matter since such matter under impact will tend to glance off the round surface of the bolt head toward the ring valve 69, to be discharged into the chamber 56, where it can do no harm.

Each piston is provided with a piston rod 82 which is, in turn, secured to a head 84 by a pin 86, the design being generally the same as that of an airplane radial engine, and the rod of one of the pistons is secured by two pins 86, as shown in Fig. 3. The head 84 is carried by a pin 85, which extends from a counterbalancing segment 88 carried by the upper end of the shaft 28.

When the shaft 28 is rotated, the head 84 rotates relative to the pin 85 and also describes a circle concentric with the axis of the shaft 28.

By connecting one of the piston rods to the head 84 by means of two pins 86 instead of one such pin, the vibration of the parts which would otherwise occur is eliminated or at least minimized.

If it is desired to operate the compressor at less than full volumetric capacity, one or more ports spaced inwardly from the intake valve 10, may be provided in the cylinder linings 60 so as to permit some of the gas drawn into the cylinder on the suction stroke to by-pass back into the chamber 54 as the piston moves outwardly on the compression stroke. It will be seen that the bigger such holes are, the greater their number, and the nearer they are to the valve 10, the less the volumetric capacity of the cylinder will be. For example, if the holes are provided at 89, the volumetric capacity of the unit will be reduced to an extent measured by the volumetric capacity of the cylinder to the left of said hole as shown in Fig. 1. By this means, the volumetric capacity can be varied from full to substantially zero without changing any other part of the compressor or its speed. Also note that instead of using suction ports such as 68 and a suction valve 70, as a means of drawing gas into the cylinders, ports 89, located in the walls of the cylinder liner 60, may be used. If this is done, the annular members 72 would be merely a filler ring or would be eliminated altogether by extending the cylinder liner 60 to the present position of outer edge of the annular members 72.

In order to insure sufficient heat dissipation, the stator is provided with vertically disposed ribs 92 which are made of copper or other good heat conducting material and which project into the passages 49 so as to be in the path of the lubricant flowing downwardly from the crankcase 30 through the pipes 50.

The casing 16 is also provided with an inlet conduit 94 which leads from a thermostatically controlled source of liquid refrigerant into the interior of the casing whereby, in response to temperature of a predetermined value, a small amount of liquid refrigerant is admitted for direct expansion inside the casing to cool the latter and the lubricant circulating therein. The evaporation of liquid refrigerant inside of the casing 16 is only resorted to when the cooling capacity of the low pressure refrigerant drawn through the inlet 47 is insufficient to maintain the temperature of the compressor at the desired value.

Operation

When in use, the compressor is connected at 41 to the evaporator or low pressure side of a refrigerating system, and is connected at 57 to the condenser or the high pressure side of such system, and the motor is started. The motor operates the lubricant circulating pump and the radial pistons and, as above pointed out, it does not matter in which direction the motor runs because, by provision of the valves 40 and 41 and the valves 46 in the housings 42 and 43, the pump will circulate the lubricant whether the motor runs in one direction or the other. The action of the pistons creates reduced pressure within the casing 16 and thus exerts suction, through the inlet 47, on the evaporator so as to draw the evaporated refrigerant and such refrigerant as may still be in the liquid state, from the evaporator into the casing 16 of the compressor. The

refrigerant gas now flows upwardly into the chamber 54, and through the intake ports 68 (or 89 if a suction valve 70 is not used), past the now unseated valve 70 into the cylinders 5 whose pistons are moving through their suction strokes. The gas compressed by the pistons is discharged past the valves 69 into the high pressure chamber 56 and through the outlet 57 to the condenser to be cooled and liquefied and returned to the evaporator. As stated, the volumetric capacity can be more or less decreased by providing one or more holes located at 89 or at other points along the length of the cylinder liner 60.

The lubricant propelled by the pump travels upwardly through the bore 29 in the shaft 28 into the crankcase 30 to fill the latter so as to insure that all moving parts are at all times bathed in lubricant. From the crankcase, the lubricant overflows through the pipe 50, over the stator, to cool the latter, and down through the passages 49 into the sump 44 in the lower portion of the compressor. It will be noted that by this arrangement and by provision of the seal 53A, the lubricant does not reach the rotor or the gap between the stator and the rotor.

Since the lubricant flows downwardly through the passages 49 through which the low pressure, low temperature refrigerant flows upwardly, there will be heat transfer between the lubricant and the refrigerant which results in cooling the lubricant and in evaporating any liquid refrigerant that may have been drawn in from the evaporator. As stated, the cooling action of the low pressure refrigerant normally drawn from the evaporator, if not sufficient, can be supplemented by delivery of the required amount of liquid refrigerant to be directly evaporated or expanded inside the compressor.

Dismantling, assembly and servicing

In order to have access to the pins 86, the crankpin 84, the counterbalance 88, or other adjacent parts, it is merely necessary to disengage the bolts 90 and remove the cap 92a.

To have access to any of the cylinders, their valves and their pistons, it is merely necessary to disengage the bolts 66 and remove the heads 65.

It will be noted that, except for the exterior fastening bolts 66 and 90, no bolts or nuts are used and that all the moving parts and their bearings have a floating fit, one with the other. For example, if the head 65 is removed, the cylinder liner 60, together with all other parts between it and the head 65, may be installed or removed. Also, by virtue of the floating fit, the parts are capable of adjusting or locating themselves, thereby providing a flexible assembly which adapts itself to change in temperature and to a reasonable amount of wear.

Servicing of a unit such as that described is also rendered very easy and inexpensive. For example, if one of the valves 69 or 70 should need replacement, or if a piston ring should break, etc., the service man in the field need only shut the compressor off from the refrigerating system, remove the head 65, the spring 80 and the plate 74. This will give him access to the cylinder liner, to the piston, to the annular member 72 and to both of the valves, so that any or all of these parts can now be repaired or replaced. Such an operation does not require much skill or time and can be carried out without an assortment of especially designed tools. By making the parts standard, they become interchangeable, and

mass production and assembly of compressors is made possible.

By removing the bottom plate 95 the rotary pump 34 and the valves 40 and 41 may be serviced, and after the pump 34 and its key 35 have been removed, the compressor base 10 can be dropped by loosening bolts 19. This will give access to the housings 42 and 43, to the stator 24 and rotor 26.

By removing the rotor nut 33 and the bolts 25 the stator and rotor can be slipped out of the casing 16.

To detach the casting 51 from the casing 16, the bolts 52 are disengaged, and assuming that the plate 82a has already been removed and the pins 86 pulled out, the shaft 28 and the bearing 53 can be taken out. This leaves the compressor completely dis-assembled and any worn parts can be replaced. Because all parts which are subject to wear are inserted into, rather than built into the frame pieces, a complete overhauling of the compressor takes a very short time, as standard parts can be ordered from a warehouse thereby eliminating extensive and costly machine work.

What I claim is new and desire to secure by Letters Patent:

A gas compressor comprising a casing, a head detachably secured to the upper end of said casing, said head being cored to provide a crank case and a first chamber for receiving compressed gas, said head, in cooperation with the upper end of said casing, also forming a second chamber for receiving low pressure gas, a plurality of cylinders carried by said head and having intake valves communicating with said second chamber and discharge valves leading to said first chamber, 30 pistons for said cylinders, driving means in said crank case for actuating said pistons, a motor

15
25

in said casing, a hollow shaft driven by said motor and operatively connected to said driving means, said shaft extending from near the bottom of said casing into said crank case, there being passages formed between said motor and said casing, a pump located in said casing and operated by said shaft for conveying lubricant from said casing, through said shaft, into said crank case, a spout for returning lubricant from said crank case, through said second chamber, to the upper ends of said passages, means for conveying low pressure gas into said second chamber, and means for conveying compressed gas from said first chamber.
